UNITED STATES PATENT OFFICE.

STEPHEN T. KELLEY, OF GREAT FALLS, MONTANA.

DEVICE FOR WATERING STOCK.

1,137,214.

Specification of Letters Patent. Patented Apr. 27, 1915.

Application filed August 10, 1914. Serial No. 856,066.

To all whom it may concern:

Be it known that I, STEPHEN T. KELLEY, a citizen of the United States, residing at Great Falls, in the county of Cascade and 5 State of Montana, have invented a new and useful Device for Watering Stock, of which the following is a specification.

This invention relates to watering devices especially designed for use in connection 10 with watering troughs for stock.

One of the objects of the present invention, is to provide an automatic water controlling device that will maintain a uniform supply of water in the drinking trough under all conditions.

Another object of the invention is to provide an automatic water controlling device capable of being operatively connected with any form of water supplying conveyers or 15 containers.

A further object of the present invention is to provide an automatic water controlling device of general improved construction, whereby the device will be extremely simple, 20 durable and inexpensive in construction, as well as being convenient, practical, serviceable and efficient in its use.

With the foregoing and other objects in view which will appear as the description 25 proceeds, the invention resides in the combination and arrangement of parts and in the details of construction hereinafter described and claimed, it being understood that changes 30 in the precise embodiment of the invention 35 herein disclosed can be made within the scope of what is claimed without departing from the spirit of the invention.

The invention has been illustrated in its preferred embodiment in the accompanying 40 drawings, wherein—

Figure 1 is a side elevation of the watering device applied to a water tank; the drinking trough being shown in section. Fig. 2 is a vertical section through the 45 watering device, shown applied to the ordinary water pipe.

In carrying out the present invention, there is provided a valve casing, which is preferably, although not necessarily, constructed of stock material or parts, composed of a sleeve 1 which is interiorly threaded for the reception of the respective inner ends of the exteriorly threaded reducing nipples 2 and 3. The reducing nipples 2 and 3 are provided at their respective outer ends, or the ends remote from the

sleeve 1, with non-circular flanges for the reception of wrench jaws or the like, and the reducing nipple 3 is interiorly threaded for engagement with the exteriorly threaded 60 pipe section or spout 5, which is held against rotation, relative to the reducing nipple 3, by means of the jamb nut 6 and the washers or wear plates 7.

A supporting bracket or standard 8 is 65 secured to the end of the pipe or spout 5 which is remote from the reducing nipple 3, by means of rivets or other securing means, said bracket having fulcrumed at its upper end, a bell crank lever 9, as shown at 10. 70 The arm 11 of the bell crank lever 9 oscillates, as will later appear, within a slot 12 formed in the outer end of the pipe or spout 5, said arm 11 being connected with the valve 13 through the instrumentality of a link 14, 75 the valve 13 being guided to its seat 15, by means of a plurality of guide pins or fingers 16, which are secured to and project perpendicularly from the valve 13, which has secured to its operative face, a washer or 80 gasket 16', in order to insure a water tight joint.

In order that a predetermined quantity of water may constantly be maintained in the drinking trough 1, a float valve 18 is provided, 85 said valve is connected to one arm of the bell crank lever 9 by means of a link or rod 17.

In practical operation, when a quantity of water has been consumed by the stock or the like, sufficient to cause the water level in the drinking trough 1 to drop below a predetermined height, the float 18 in descending, will, through the instrumentality of the link 17, cause the bell crank lever 9 to oscillate 90 on its fulcrum or pivot 10, thereby causing the arm 11 of the bell crank lever 9 to be moved in the slot 12 toward the valve casing 1, thus moving the valve 13 from its seat 15, 95 as shown in dotted lines in Fig. 2, allowing a fresh supply of water to flow through the valve casing 1 and spout 5 into the drinking trough 1, from either the tank B or pipe P 100 according to which is the more convenient to be employed under the conditions to be 105 met.

Having thus described the invention, what is claimed as new is:

A device for watering stock, including a water supply, a bushing having a restricted inlet and an enlarged outlet connected to the supply, a tubular casing connected exteriorly 110

of the enlarged outlet of the bushing, a second bushing connected in the opposite end of the casing and having a reduced internally threaded bore, an externally threaded pipe extending therethrough and having one end projected into and out of contact with the tubular casing, such extended end forming a valve seat, the outer end of the pipe being provided with a spout and with a longitudinal slot in the upper wall thereof, a clamp surrounding the spout and having a pair of arms extending upwardly therefrom, said arms being spaced apart so that the space thereof alines with the slot of the spout, a float actuated bell crank lever pivoted between the arms and with one end thereof movable in the slot and projecting into the spout end of the pipe, a disk valve

having a plurality of guide pins mounted in the casing, the pins being extended into the pipe from within so that the valve is slidable to and from the seat and is carried by the pipe, said valve being of lesser diameter than the casing and out of contact therewith, an apertured lug carried by the valve and upon the same side thereof as the pins, and a link connected to the apertured lug of the valve and to the end of the bell crank lever within the pipe.

In testimony that I claim the foregoing as my own I have hereto affixed my signature in the presence of two witnesses.

STEPHEN T. KELLEY.
